Primary Examiner — Brett Miller*Assistant Examiner* — Yolanda Robinson(74) *Attorney, Agent, or Firm* — Richards Patent Law P.C.(57) **CLAIM**

The ornamental design for an automobile handle, as shown and described.

DESCRIPTION

FIG. 1 is a rear-left side isometric view of a driver's side embodiment of an automobile handle showing my new design;

FIG. 2 is an inverted, relative to FIG. 1, isometric view thereof;

FIG. 3 is a left view thereof;

FIG. 4 is a right view thereof;

FIG. 5 is a top view thereof;

FIG. 6 is a bottom view thereof;

FIG. 7 is a back view thereof;

FIG. 8 is a front view thereof;

FIG. 9 is a rear-right side isometric view of a passenger's side embodiment of an automobile handle showing my new design;

FIG. 10 is an inverted, relative to FIG. 9, isometric view thereof;

FIG. 11 is a right view thereof;

FIG. 12 is a left view thereof;

FIG. 13 is a top view thereof;

FIG. 14 is a bottom view thereof;

FIG. 15 is a front view thereof; and,

FIG. 16 is a back view thereof.

(Continued)

Those portions of the figures that are presented in broken lines merely illustrate the environment of the design and are not part of the claimed design.
